UNITED STATES PATENT OFFICE.

DONALD T. McCALL, OF JACKSON, MICHIGAN.

oval and round cardboard cutting machine.

No. 822,976.

Specification of Letters Patent.

Patented June 12, 1906.

Application filed December 10, 1903. Serial No. 184,677.

To all whom it may concern:

Be it known that I, DONALD T. McCALL, a citizen of the United States, residing at the city of Jackson, in the county of Jackson and State of Michigan, have invented a new and useful Oval and Round Cardboard Cutting Machine, of which the following is a specification.

My invention relates to improvements in oval and round cardboard cutting machines in which a reciprocating table operates in conjunction with a rotating cutting-knife adjustably secured upon a sweep-arm, to which are also secured an adjustable pressure-roller and an adjustable ornamental wheel for making a bead; and the object of my improvements is to provide a machine that is simple in construction and easy to operate and that will cut a perfectly true oval or circle. I attain this object by the mechanism illustrated in the accompanying drawings, in which—

Figure 1 is a side elevation, partly in section. Fig. 2 is a end view, partly in section, of one portion of the machine. Fig. 3 is a top view of the sweep-bar and an attachment secured to said bar.

Similar letters refer to similar parts throughout the several views.

30 A is the metal upright frame, secured at the base to the top side of the sills O O crosswise of the table M. The side sills O are secured to the crosswise end sills N N by bolts. The brace-bracket S is secured to the 35 side sills O and to the metal frame A. There are two outwardly-projecting brackets R R secured at one end to the metal frame A. In the outer ends of the brackets R each one has a journal-bearing in which the shafts

40 E' and E² revolve. The upper shaft E' has the handle D secured to it, by which the machine receives its reciprocating motion given to the table M. The shafts E' and E² have made integral to each of them an L,

45 and through these L's a hole is made for the reception of the staple-crank pitman C, which is secured to the L's by set-screws. At the base of the lower shaft E² is made integral to it an outward projection U. To

50 this part the sweep-bar G is secured by the bolt W, and on this bolt the sweep-bar G oscillates. In the part U a thumb-screw is used for regulating the cut of the knife and for holding the sweep-bar up when not in use. To the table M are secured two stand-

brackets F, one on each side of the table. To these brackets F are secured the crosswise parallel bars B, which are spaced a sufficient distance apart to allow the staple or crank-pitman C to pass in between them. The 60 table M has secured to its side edges a strip of band-iron P, which moves on ledges on the sills O, causing little friction. The sweep-bar G has located on it three slidable blocks. The pressure-wheel V travels on the inside of 65 the cut, being pivoted on the stem Z, and conforms itself to the circle being cut. At the top of this block there is a threaded bolt Y for regulating the pressure on the cardboard being cut. This block when set is secured 70 to the sweep-bar G by a set-screw, the slidable block H being secured to the bar G. At the lower end of this block there is adjustably secured the square knife-block I, 75 having the knife J secured to the block I, as shown in Fig. 1. The slidable block X is secured to the bar G and has a wheel journaled on its axle. The face of this wheel may be made in any ornamental form desired to make a mark or bead on the outer 80 edge of the oval cut. On the outer end of the sweep-bar G is located a weight Q for gradually forcing the knife into the cardboard. K is a spring-clamp secured to the table M by a bolt for holding the cardboard 85 L firm on the table while being cut. There are two of these springs or clamps used, but only one shown.

Having described my invention, I will now describe the operation.

The cardboard L is laid on the table M and secured by the springs K. The size of the oval to be cut is then determined crosswise. The slidable block H is then set on the sweep-bar G. The length of the oval is then determined. The adjustable crank C is then set in the L's apart of the shafts E' and E² to give the desired travel to the table M. To cut a circle, the staple-crank C is set directly in the center of the perpendicular shafts. 95 Then when the handle D is turned the table M will stand still. It will be seen the crank C determines the travel of the table. When the handle D is turned to the right when standing in front of the machine, there will be cut 100 a perfect oval, or circle.

I am aware that prior to my invention oval-cardboard-mat-cutting machines have been made with stationary tables. I therefore do not claim such a combination broadly; but 110

What I do claim as my invention, and desire to secure by Letters Patent, is—

In a machine of the character described, a fixed supporting-frame, a truss-frame having outwardly-projecting brackets secured above said fixed frame, bearings in said brackets in which are journaled perpendicular shafts coupled together by an adjustable staple-crank which operates in conjunction with parallel bars secured to brackets fixed to a table slidable on the fixed supporting-

frame, and means for rotating the staple-crank whereby a positive reciprocating motion is imparted to the table, substantially as described.

In testimony whereof I have signed my name to this specification in the presence of two subscribing witnesses.

DONALD T. McCALL.
